UNITED STATES PATENT OFFICE.

ALFRED WOODWARD, OF DENVER, COLORADO.

DUMPING BODY FOR TRUCKS.

1,413,551.

Specification of Letters Patent. Patented Apr. 18, 1922.

Application filed March 1, 1920. Serial No. 362,361.

To all whom it may concern:

Be it known that I, ALFRED WOODWARD, a citizen of the United States, residing at the city and county of Denver and State of Colorado, have invented certain new and useful Improvements in Dumping Bodies for Trucks; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a simple and efficient dumping body which may be easily handled for quick discharge of the load.

Briefly the invention comprises stationary 20 transverse members of a frame having the ends thereof on an inclination with hooks at the lowermost points. The movable portion of the body comprises transverse members through which extend longitudinally 25 disposed rods which bear upon the tops of said stationary transverse members and are movable from end to end thereof. The movable transverse members carry the dumping body, and means are provided for manipulating cables connected with said rods so that the body may be moved from side to side, said movement being limited by said 30 hooks. A latch is provided for retaining the body in upright position when carrying a load, and the sides of the body are hinged both at top and at bottom, so that 35 said sides may be swung from either point.

In the drawings:

Fig. 1 is a side elevation showing the invention.

Fig. 2 is a view indicated in general by the lines 2—2 of Figs. 1 and 4.

Fig. 3 is a partial section on the line 3—3 of Fig. 4.

45 Fig. 4 is a section on the line 4—4 of Fig. 2.

Fig. 5 is a view taken at the same point as Fig. 4, showing the body in dumping position.

50 Fig. 6 is a detail of the upper hinge indicated by arrow 6 of Fig. 5.

Fig. 7 is a view at right angles to the showing of Fig. 6, as indicated by arrow 7.

Longitudinally extending timbers 10 of 55 the truck frame carry stationary transverse members 12, whose ends are cut at an in-

clination as indicated at 14, the lowermost points being provided with hooks 15.

The movable body comprises transverse timbers 16, connected to longitudinally extending side rails 18, the latter carrying the bed 20. Stationary ends 22 are provided and also swinging sides 24. A pair of rods 26 extends longitudinally through the transverse timbers 16 from end to end of the body, these rods being provided with sprockets 28 over which a chain 30 passes. The rear ends of the rods may be squared as at 32, to receive a crank 34 for turning either of said rods, one rod being turned by the other through the medium of the chain 30. One rod has a cable 36 connected thereto and wound therearound, with its opposite end connected to the timber 10 on the opposite side of the truck framework. The other 75 rod is provided with a similarly connected cable 38, connected with the opposite timber 10. The rods 26 are provided with rollers 40, which travel along the tops of the stationary transverse members 12. 80

In order to retain the dumping body in upright position, certain of the timbers 16 on the movable body are provided with brackets 42, between which a movable latch 44 is pivoted, the lower end of the latch being opposite and adapted to enter a notch 46 in a retaining member 48, secured to the stationary transverse members 12 below. The latches 44 are operated by means of lever arms 50 and a longitudinally extending 90 cable 52.

The lower edges of the side walls 24 are hingedly connected with the dumping body by means of eyes 60 on straps 62, secured on the sides 24, and eyes 64 on the body. When 95 the walls 24 are in closed position, as in Figures 1 and 4, the eyes 60 and 64 are in alignment and are retained therein by means of pins 66, secured to a longitudinally extending rod 68, slidable in bearings 70, and 100 operable by means of a handle 72 for moving into and out of operative position.

The upper hinge mountings for the walls 24 comprise U-shaped brackets 74, which are secured to the end members 22, as at 76, and 105 are provided with transverse notches 78, which receive pivoting stems 80, secured to the walls 24, as indicated at 82. When the pivoting stems 80 are in position, as shown in Figs. 6 and 7, they are retained by means 110 of vertically positioned, headed pins 84. When these upper hinges are released, the

walls 24 may be swung outwardly on the hinges at 60 and 64. To limit the amount of such movement the brackets 74 are provided with offset notched lugs 86, adapted to 5 receive links of a chain 88, connected at 90 with the pivoting stems 80.

In operation of the device, the movable body may be moved from upright position, either to one side or the other by turning 10 one of the rods 26 with the crank 34, the rollers 40 moving along the transverse members 12 to a position as indicated in Fig. 5, where the hooks 15 receive the corresponding rod 26 and prevent further movement. In 15 order to permit the body to be moved to this position, it is first necessary to pull the cable 52 to release the latches 44, so that the body may move laterally. By moving the lever 72 the hinges at 60, 64, will be released to 20 allow the respective side wall 24 to open, as shown in Fig. 5, and discharge the load. The crank may then be placed on the other rod 26 and the body returned to upright position, the latches 44 being allowed then 25 to re-enter the slots 46 in the retainers 48. In order to prevent vertical movement of the body, the brackets 42 may be provided with offset fingers 142, which underlie the transverse portions of the retainers 48 on opposite sides of the slots 46.

In case it is desired to let down the upper edges of the walls 24, so that they swing about the hinges 60, 64, the pins 84 are removed and then chains 88 adjusted to allow 30 the desired amount of movement.

In order to make the release of the lower hinges 60, 64 automatic, a screw eye 100 is mounted in the center one of the stationary transverse members 12, this eye 100 having

two chains 102 connected therewith at one 40 end and provided at their other ends with hooks 104 to engage in eyes 106 in bell cranks 108 connected to operate the rods 68. The chains 102 are of such length that when the body approaches the limit of its lateral motion during discharge movement, the chain on the respective side is drawn taut, thereby moving the respective bell crank to reciprocate its rod 68 and withdraw the pins 66. When the body is righted, the lever 72 is used 45 to return the pins 66.

However, when the upper edges of the sides 24 are to be lowered about the hinges 60, 64, as pivots, the hooks 104 must be removed from eyes 106 to prevent operation 50 of the bell cranks 108 and withdrawal of pins 66, which would result in collapse of the sides 24.

I claim:

In a dumping device having a framework 60 and relatively stationary transverse members attached thereto, a body transversely movable on said transverse members and tiltable thereon, doors on said body member and means for automatically opening said doors 65 at the bottom when the body tilts, said means consisting of a bar extending longitudinally of said body, hinges close to said bar, pivot pins in said hinges, means on said bar for moving said pivot pins out of engagement with one of said hinge members, a bell crank lever connected to said body, a link connecting one end of said bell crank with said rod and chains connecting the other end of said bell crank to said framework. 70

In testimony whereof I affix my signature.

ALFRED WOODWARD.
